PROCESS OF SHOEMAKING CHARACTERIZED BY THE EMPLOYMENT OF A SPECIAL STIFFENER

Walter H. Heaton, Franklin, and Harry H. Straw,
Boston, Mass., assignors to Beckwith Manufacturing Company, Dover, N. H., a corporation of New Hampshire

Application January 10, 1946, Serial No. 640,244

3 Claims. (Cl. 12—146)

1

Our invention relates to shoemaking and comprises an improved shoe stiffener, the process of making the improved shoe stiffener, and a process of shoemaking characterized by the use of our improved shoe stiffener.

The shoe stiffener of our invention is particularly adapted for use in conjunction with the general process of shoemaking which has come to be known in the trade as the "California process." The salient features of the "California process" consist in uniting off the last an upper and insole, these elements being first carefully cut and marked prior to assembly so that in the process of stitching them together draft and fullness are imparted to obtain a properly shaped shoe. This is a departure from ordinary shoemaking methods in which the shape of the shoe is obtained by stretching an upper over a last, trimming off surplus portions of the overlasted margin, and securing the upper to the insole while both members are in position on the last. In accordance with the "California process" a last is inserted after the upper and insole have been united for the purpose of shaping the shoe and also to hold it in shape during the operation of attaching an outsole.

It has long been thought that it was impossible to incorporate into a "California process" shoe a toe stiffener or box toe of the conventional sort. In ordinary shoemaking a box toe stiffener is inserted between the lining and the upper before the shoe is lasted, and the stiffening and adhesive compound in the stiffener is activated when it is inserted. The subsequent lasting operations are carried out before the box toe becomes stiff, with the result that the stiffening of the box toe takes place while the shoe is on the last. During the stiffening process the box toe becomes adhesively united to the lining and the inner surface of the upper. In the "California process" the lining does not usually extend forwardly of the throat. Consequently if a box toe stiffener of conventional character were incorporated into the structure of the shoe and activated prior to the insertion of the last, the box toe would adhere not only to the upper but also to the surface of the last, and the withdrawal of the last would be impossible.

We have discovered that it is possible to produce a shoe stiffener which can be successfully incorporated into a shoe manufactured according to the "California process." A shoe stiffener capable of such use involves a novel process for manufacturing the stiffener, as well as a novel method of employing it in the shoemaking process.

2

The most important object of our invention is to improve the quality and appearance of the California type shoe by the incorporation therein of a shoe stiffener.

Another object of the invention is to provide a process in which it is possible to activate a shoe stiffener secured within an upper in such condition that it is exposed on the interior of the shoe and at the same time render it possible to insert and withdraw a last without causing the shoe stiffener to become cemented to the last.

In one aspect our invention comprises a fibrous shoe stiffener saturated through approximately one half only of its thickness with a stiffening and adhesive compound, while the other half and one surface thereof is left relatively soft, flexible and porous.

In another aspect our invention comprises a shoemaking method including the step of introducing an activating agent through a porous and flexible portion of a shoe stiffener to a layer thereof saturated with a stiffening and an adhesive compound disposed against the inner surface of a shoe upper.

These and other objects and features of our invention will be more readily understood and appreciated from the following detailed description of a preferred method for producing our improved shoe stiffener, together with a description of a preferred manner of incorporating the improved stiffener into the structure of a shoe, the same being illustrated in the accompanying drawing, in which

Fig. 1 is a diagrammatic view in cross section suggesting the manufacture of our improved shoe stiffener, the elements therein being shown on an enlarged scale,

Fig. 2 is a plan view of a stiffener made in accordance with our invention, and

Fig. 3 is a view in cross section through the toe end of a shoe including in its structure our improved stiffener.

Referring more particularly to Fig. 1, the shoe stiffener of our invention is preferably produced by first providing a sheet of double napped flannel, although single napped flannel, felt with a lofty pile, or other similar fibrous sheet material may be substituted with little effect on the results. As used herein, the term "nap" or "napped" refers to any fibrous material of which one surface is covered with relatively long fibers or filaments free at one end and anchored at the other end to the material. For purposes of illustration we have shown in the drawing a sheet 10 of double napped flannel. The first operation is to feed the

sheet 10 between a pair of rollers 12 and 14. The roller 12 is continuously supplied with a film 16 of a stiffening and adhesive compound. There is a wide range of materials suitable for the purpose, such as solvent-softening lacquers and cements including nitro-cellulose compounds, vinyon, ethyl acetate, ethyl cellulose, and materials soluble in ketones, alcohols and other organic solvents. Another type of compound comprises the water soluble gums, starches or resins. For example, polyvinyl alcohol, sodium carboxymethyl-cellulose, British gum, gum arabic and corn starch are all materials capable of use in the process of our invention. Furthermore we contemplate the use of thermal setting compounds such for example, as bakelite or one of the melamines. The foregoing list of compounds is to be taken as suggestive of a few suitable stiffening and adhesive compounds. Others, equally useful, will suggest themselves to those skilled in the art as equivalents of those above mentioned.

One specific water-softening compound that may be employed with good advantage is a mixture of two parts dextrin, one part corn starch and one part pearl gum. The ingredients are mixed in a small quantity of cold water and then poured into a suitable volume of hot water. After thorough mixing, the compound is ready to be used in carrying out the process herein described. The lower roller 14 is dry and serves merely to support and feed the sheet 10. The action of the rolls 12 and 14 is to load the compound 16 into one surface of the sheet 10 and to saturate the sheet 10 through approximately one half of its thickness. In order to secure such saturation and loading, the sheet 10 is fed through the rollers so that the loading takes place against the direction of the nap. The upper nap of the sheet 10 is shown at 18 and the lower nap suggested at 20. The extent of the penetration of the compound 16 into the sheet 10 is of course partially determined by the pressure exerted by the rolls 12 and 14 on the sheet 10 and may be varied by adjusting their spacing. However, it is easily possible to secure an adjustment which will cause the compound 16 to penetrate approximately through one half the thickness of the sheet 10, and we have discovered that this amount of penetration is suitable in practice. The other half of the sheet is left soft and porous.

From the loading operation described above the sheet 10 is passed through a drying tower in which the solvent is evaporated leaving a relatively stiff, dry deposit of the compound in the sheet. After the drying operation has been accomplished, the sheet is passed through calender rolls adjusted to compress it to proper thickness. Subsequently the sheet may be dried out in blanks suitably shaped for shoe stiffeners. The final operation is to skive the edges of the stiffeners so that they will blend easily with the surface of the upper of the shoe and not leave uncomfortable or unsightly ridges. The skiving, of course, is carried out from the unsaturated surface of the shoe stiffener. The finished stiffener exhibits one surface which is relatively soft, flexible and porous, being entirely suitable for incorporation into an unlined shoe.

In Fig. 3 there is shown a partially constructed shoe including an insole or platform sole 26 to the marginal edge of which is stitched the out-turned margin of an upper 28, with one of our improved stiffeners 30 caught in the stitching 32 which united the upper and the insole. The usual binding strip 34 is sewn to the margin of the assembly

by a line of stitching 36. The stiffener 30 is secured with its coated surface against the inner face of the upper 28, and the inner untreated surface of the stiffener 30 is exposed in the interior of the shoe.

We refer to the untreated portion of the stiffener as "soft and flexible" in the sense that the treated portion is relatively hard and stiff, and the expression "soft and flexible" is hereby defined for the purposes of this specification and the appended claims as covering any portion or surface of the stiffener which has a character of such nature that it may be used as an exposed surface next the foot of the wearer in the interior of the shoe.

Before the last is inserted in the shoe the saturated portion of the stiffener is activated by introducing into the interior of the shoe an agent to activate the stiffening and adhesive compound. For stiffeners impregnated with a soluble compound a solvent may be sprayed against the untreated surface from a goose-neck nozzle 38 introduced into the interior of the shoe adjacent the stiffener. The solvent easily penetrates the untreated porous portion of the stiffener 30 and activates the stiffening and adhesive compound loaded into the unexposed surface thereof. Obviously the solvent may be swabbed on the stiffener instead of being sprayed. Where a thermal setting stiffening and adhesive compound has been used, the entire shoe may be heated, or a blast of steam or hot air introduced into the interior thereof. In any case the activation of the compound is followed by the insertion of the last. The last presses the temporarily flexible stiffener against the inner surface of the upper 28 and cements the two together. While the last is in place, a midsole or outsole is secured to the bottom of the shoe, and the last is then withdrawn. During the sole attaching operation and while the last is in the shoe, the solvent evaporates to leave the stiffener 30 molded to shape and relatively stiff and hard. Inasmuch as there is no stiffening compound in contact with the surface of the last, withdrawal of the last is not impeded. The resulting shoe will present an appearance and quality every bit as fine as that obtained in the toe end of a shoe manufactured by conventional methods.

It is to be understood that the shoe manufacturing process above described merely illustrates one of a great number of ways in which our improved stiffener may be incorporated into the structure of a "California process" shoe. The details of upper and sole structure may be varied at will, and the introduction of the activating agent may be accomplished in any suitable manner.

The process of making shoe stiffeners and the stiffeners herein disclosed are the subject-matter of our divisional application Ser. No. 19,736, filed April 8, 1948.

Having thus disclosed our invention what we claim as new and desire to secure by Letters Patent is:

1. A process of shoemaking which comprises providing a shoe stiffener of double napped fibrous material having one half its thickness soft and flexible and the other half saturated with a soluble stiffening and adhesive compound, securing together off the last an upper, an insole and said stiffener, the saturated half of said stiffener being disposed against the inner surface of the upper, introducing a solvent through the soft flexible half of the stiffener to the saturated half

thereof, inserting a last to shape the shoe and press said stiffener against said upper, permitting said solvent to evaporate, and withdrawing said last.

2. A process of shoemaking which comprises providing a shoe stiffener saturated on one surface with a stiffening and adhesive compound and porous and flexible on the other surface, assembling and uniting off the last an upper, an insole, and said stiffener, the saturated surface of said stiffener being disposed against the inner surface of said upper, introducing an activating agent through the soft flexible surface of the stiffener to the saturated surface thereof, inserting a last in the shoe to press the stiffener against the upper and cement it thereto, and withdrawing the last.

3. A process of shoemaking which includes the steps of providing a box toe stiffener saturated on one surface and loaded throughout approximately only one-half of its thickness with a stiffening and adhesive compound and being porous and flexible on its other surface, assembling and uniting off the last a vamp, an insole and said stiffener, the saturated surface of the stiffener being disposed in contact with the inner surface

5 10 15 20 25

of said vamp, introducing an activating agent through the porous flexible surface of the stiffener to the stiffening and adhesive compound thereon and to the saturated surface thereof, inserting a last in the shoe to press the softened stiffener against the vamp and cement it thereto, and withdrawing the last after the stiffener has taken its shape therefrom.
